CONTAINER CLOSURE

Otto Höchstädtér, Munich, Germany

Application October 18, 1934, Serial No. 748,935
In Germany October 20, 1933

3 Claims. (Cl. 215—39)

This invention relates to a closure for containers of all kinds, more particularly bottles, glasses and the like, which is held on the container by means of an external ridge on the opening. Closures of this kind are known in various constructions, as for example, crown corks and claw stoppers for bottles. These however, do not fulfill all the requirements that they should be not only cheap in manufacture and simply and securely attached to the container, but also readily removed therefrom without it being possible to open the closure unintentionally.

These requirements can be met according to the invention by the closure being formed from two superposed caps, both of which separably are readily removed from the container. According to the invention, above the actual closure cap a securing cap is arranged, the marginal part of which is folded in the manner of a crown cork, pressed against the holding parts of the closure cap and provided with a tongue.

Several constructional examples of the invention are illustrated in the accompanying drawing, in which

Fig. 1 shows the closure according to the invention in side elevation.

Fig. 2 is a plan of this closure,

Fig. 3 shows the closure as seen from below,

Fig. 4 is a side elevation of a further constructional form of the closure,

Fig. 5 is a view from below of the closure according to Fig. 4,

Fig. 6 shows a side elevation of the closure according to Figs. 1 and 2 pressed against a bottle neck and partly cut away.

Fig. 7 is a plan of a box with the closure according to the invention.

In the drawing 1 is a securing cap, the marginal part 2 of which according to the invention, is crimped. This securing cap is arranged over the actual closure cap which contains a packing. This closure cap may have various shapes and in Figs. 1 to 3 it is illustrated as a claw or expandible cap 3, with packing plate 3a, and in Figs. 4 and 5 is a crimped cap or crown cork 4 with packing 4a. The securing cap is of practically the same shape for both the closure caps illustrated. According to the invention it has a tongue 5 for tearing off, which is preferably formed from the metal cover part of the cap as shown in the drawing, the marginal part connected with it being bounded by a double radial perforation 7.

At the beginning the tongue 5 is provided with a flat edge 5' so that between the beginning of

the tongue and the cover there is an opening 5'' which facilitates gripping the tongue.

When the closure cap and securing cap are applied to the container, for example a bottle neck, it is important that the two caps should be held one within the other. For this purpose the securing cap has holding members 8 and 9 provided on the marginal part 2. As shown in Fig. 3 the holding members 8 are made short and embrace the edge or the claws 10 of the closure cap. On the other hand the holding members 9 are made so long that they enclose claws 10 so that these long holding members are drawn in and held fast when the closure is placed on the container. The securing cap is in this way protected from any unintentional loosening, for example, in transport. The arrangement of the longer holding members is preferably such that the one holding member 9 is attached to the perforated marginal part 6 and the other holding member is at the opposite edge of the cap.

In the advantageous construction of the closure illustrated in Figs. 4 and 5 in which both caps are made in the manner of a crown cork it is possible in some circumstances to dispense with the holding members, since here the similar superposed caps will be held firmly one within the other with a small pressure between their marginal parts 2. In general however, it will be sufficient if only two of the longer holding members 9, according to Fig. 3, are provided as shown in Fig. 5.

The above described construction of the closure, which is intended more particularly for bottles and glasses, has the great advantage that it is not only comparatively cheap to make, but, in addition, it can be placed on the container in a very simple manner. When the new container is used for bottles the well-known devices for applying the stopper may be employed. It is also important that the closure cap and securing cap when combined according to Figs. 1 to 5, should be pressed on the container simultaneously in one operation. In this pressing operation, with the known tools, the inner part 11 of the marginal portion of the securing cap is pressed tightly on to the holding part of the closure cap as illustrated in Fig. 6 by way of example, to a claw cap. This may, of course, also be constructed as a spreading cap.

The closure is opened by the tongue 5 being raised somewhat from the cover of the securing cap, and then being gripped and torn downward strongly in the direction A. In this way the perforation 7 is torn and the tongue, the marginal

part 6 and one holding member 9 are removed. The remaining part of the cap can easily be removed by bending back the ends in the direction of the arrows B and C. If the cap consists of hard or thick material the bending can be facilitated, if necessary, by a slot 12 in the cover part.

After removing the securing cap the actual closure cap is removed. When a spreading cap is used this is effected by pressing on the metal part of the cover. With other closure forms of closure caps these may, according to the invention, consist of suitable thin or soft sheet material so that they can easily be removed.

If the holding member 9 of the marginal part 6 of the tongue 5 is, according to the invention, made so long that it comes to lie between the cover part of the closure cap and the edge of the opening of the container the closure can be opened very easily. If the perforation is torn and the tongue is then pulled upwards the holding member 9 acts as a kind of lever which lifts off the closure.

If for the closure cap a crown cork of soft material is provided this has the advantage that the cap when required can be put back and closed on the container, for example the bottle, which is not possible with the known very hard crown corks.

The closure according to the invention has further the advantage that when using spreading cap closures it is no longer necessary for the cap or the bottle ridge to be accurately dimensioned in order to ensure satisfactory closure. While previously the smallest deviation in this respect caused trouble in the proper seating of the cap, with the present device the deviation may be considerable without the tight sealing of the closure being affected. On account of this independence of accurate dimensions it is, for example, possible to place spreading cap closures on crown cork bottles.

The closure according to the invention can be applied to containers of various kinds. Thus, for example, in Fig. 7 a closure for a rectangular sheet metal box is illustrated. In this case it is not necessary to provide over the closure cover 13 a similarly shaped crown cork cap. The metal part of the securing cap 14 can be suitably apertured, as shown at 15. For easy opening of the closure two tongues 16 are here provided.

The use of the above described closure has further the advantage that the closure can be provided with an advertising imprint or an indentation. This is not possible for example, with some known closures, for example cap closures, 5 because the closure cap is too hard.

What I claim is:

1. A closure for containers, more particularly bottles, comprising an inner expandable cap adapted to be releasably secured to the mouth 10 of a bottle, an outer crimped cap disposed over said expandable cap and adapted to secure the latter over the bottle opening, means on the outer edge of the crimped cap for embracing the outer edge of the inner expandable cap for releasably 15 retaining the expandable cap within the crimped cap when in an expanded condition, and means on said crimped cap for facilitating the removal of the outer cap.

2. A closure for containers, more particularly 20 bottles, comprising a frequently usable expandable cap, a crimped cap arranged over the expandable cap and adapted to secure the latter, retaining tongues on the edge of the crimped cap for connecting the latter to the expandable cap, and a 25 tear-off tongue indicated by perforations, said tear-off tongue lying in the plane of the crimped cap and beginning at a distance from the edge of an opening in the crimped cap, one of the 30 retaining tongues on the edge of the crimped cap forming an extension of the tear-off tongue and being continued under the edge of the expandable cap beyond the seal of the latter.

3. A closure for containers, more particularly 35 bottles, comprising a frequently usable inner crimped cap of soft material, an outer crimped cap arranged over the inner crimped cap and adapted to secure the latter, retaining tongues on the edge of the outer crimped cap for connecting the latter to the inner crimped cap, a 40 tear-off tongue indicated by perforations, said tear-off tongue lying in the plane of the outer crimped cap and beginning at a distance from the edge of an opening in said outer crimped cap, one of the 45 retaining tongues on the edge of the outer crimped cap forming an extension of the tear-off tongue and being continued under the edge of the inner cap beyond the seal of said inner cap.
